UNITED STATES PATENT OFFICE.

ABRAM NATHAN LAMPORT, OF NEW YORK, N. Y.

SAFETY-CAR.

SPECIFICATION forming part of Letters Patent No. 453,558, dated June 2, 1891.

Application filed February 18, 1891. Serial No. 381,856. (No model.)

To all whom it may concern:

Be it known that I, ABRAM NATHAN LAMPORT, of New York, in the county of New York and State of New York, have invented 5 certain new and useful Improvements in Safety-Cars; and I do hereby declare the following to be a full, clear, and exact description of the invention, such as will enable others skilled in the art to which it pertains to 10 make and use it, reference being had to the accompanying drawing, which forms part of this specification.

My invention relates to an improvement in safety-cars; and it consists in the combination 15 of a series of rectangular frames which are covered with rubber or other suitable substance, a spiral spring placed inside of the car and extending from one end to the other, and a suitable mechanism placed inside of 20 the car for holding the rectangular frames the required distance apart, as will be more fully described hereinafter.

The object of my invention is to produce a safety-car which can be placed either in front 25 of the locomotive or behind the train, and which in case of a collision will close together against the pressure of the spring placed inside of it, and thus prevent injury entirely, or very greatly lessen the effects of the collision.

30 The accompanying drawing represents a safety-car which embodies my invention, the side of the car being removed so as to show the operating parts.

A represents the safety-car, which is formed 35 of a series of rectangular frames B, of any suitable construction, and which are covered over by the rubber C and mounted upon the wheels D. In order to keep the frames B pressed a suitable distance apart, there are 40 pivoted to these frames both near their upper and lower ends a series of levers F, which are pivoted both to the frames B and to each other, and to their upper ends are fastened the weights G, which serve by their down- 45 ward pressure not only to keep the frames B pressed apart, but to assist in returning them to position after the car has been collapsed.

Placed inside of this car is a spiral spring (or springs) H, which is largest at its front end 50 and which has its smaller rear end placed between suitable supports or keepers I. In or-

der to support not only the keepers but the spring itself, there are a number of chains J, which hang down from the top of the car and make connection with them, as shown, so as to 55 keep them always in position. This spring or springs H will have sufficient power when two trains run together to gradually resist the force of the collision, and in being compressed to allow the sections B to move backward 60 with it, and if not entirely break the force of the collision at least to prevent the wrecking of the engine and cars and the loss of the lives of the passengers. After the collision, when the parts are left free to move, the 65 springs, the levers F, and weights G will serve to force the frames apart again and cause the car to assume its original shape.

As here shown, the upper front portion of the car is made to project a suitable distance 70 outward and over the top of the cow-catcher or sweep; but I do not limit myself to this precise construction.

Extending from the extreme front end of the car and from about the center of the point 75 where the safety-car is to be struck is the rod or rods K, which have its or their lower ends to bear against the axle of the front wheels, so that as the front portion of the car begins to move backward a pressure will be exerted 80 upon the front axle to assist in stopping the axle from revolving. Another rod or rods L extend from the upper front corners of the car diagonally backward and downward, so as to bear against the axle or axles of the front 85 wheels of the locomotive in front of which the safety-car is to be placed. Also, extending from the lower front corner of the car is a rod N, which extends diagonally upward and backward, and which rod is supported near 90 its center upon one of the frames B, and has its rear end to catch under and against a corresponding rod O, which extends diagonally 95 backward and downward and bears against the axle of the rear wheels. Also, extending diagonally backward and upward from the bottom of the car, just in the rear of the front axle, is a second rod P, which has its rear end to bear against the under side of the rod O, which is held down in contact with the 100 ends of the rods N and P by means of the weight Q. These rods, when the car begins to

be compressed, cause the rod O to bear against the rear axle for the purpose of checking the revolution of the wheels.

This safety-car is provided with means for attachment to the front end of the locomotive or to the car in the rear of which it is to be placed. Although two series of rods F and weights G are here shown, they may be dispensed with, if so desired, for the tension of the spring or springs will be sufficiently great to cause the sections B to spring apart into their proper positions after they are left free to move.

Having thus described my invention, I claim—

1. A safety-car composed of a series of frames which are covered by any flexible material, in combination with a spring or springs H, which are placed inside of the car and extend from end to end, substantially as shown.
2. In a safety-car, the combination of a series of frames, a series of pivoted levers con-

nected to the frames, a series of weights attached to the upper ends of the levers, and a spring or springs placed inside of the car and extending from one end to the other, substantially as described.

3. The combination of a collapsible car, a spring placed inside of the car, and rods which extend from the front end of the car and bear against the axles of the wheels, substantially as set forth.

4. The combination, with a collapsible car and a spring placed inside of it, of the rods N P O and the weight Q, connected to the rod O, the rear end of the rod O being made to bear against the axles of the rear wheels, substantially as specified.

In testimony whereof I affix my signature in presence of two witnesses.

ABRAM NATHAN LAMPORt.
